[57] CLAIM

The ornamental design for a surgical controller for heart pump, as shown and described.

DESCRIPTION

FIG. 1 is a perspective view of the surgical controller for heart pump showing our new design;

FIG. 2 is a front view thereof;

FIG. 3 is a top view thereof;

FIG. 4 is a side view thereof, the opposite side view being a mirror image thereto;

FIG. 5 is a rear view thereof; and,

FIG. 6 is a bottom view thereof.

The broken line showing in FIGS. 1-5 is for illustrative purposes only and forms no part of the claimed design.
